(57) **CLAIM**

The ornamental design for an on-body wearable charger, as shown and described.

DESCRIPTION

FIG. 1 is a perspective view of an on-body wearable charger showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof shown in use.

The broken lines in the Figures show portions of the on-body wearable charger and environment which form no part of the claimed design.

1 Claim, 7 Drawing Sheets
